UNITED STATES PATENT OFFICE

138,047

DESIGN FOR A TOY AIRPLANE BOMBER

Henry Einzig, Evanston, Ill.

Application September 6, 1943, Serial No. 111,073

Term of patent 3½ years

(CL. D34—15)

To all whom it may concern:

Be it known that I, Henry Einzig, a citizen of the United States, residing at Evanston, in the county of Cook and State of Illinois, have invented a new, original, and ornamental Design for a Toy Airplane Bomber, of which the following is a specification, reference being had to the accompanying drawing, forming part thereof.

In the drawing:

Figure 1 is a top plan view of a toy airplane bomber, showing my new design.

Figure 2 is a side elevational view of the same, and

Figure 3 is a bottom plan view thereof.

I claim:

The ornamental design for a toy airplane bomber, as shown.

HENRY EINZIG.
